UNITED STATES PATENT OFFICE

WILLIAM D. DREISKE, OF OAK PARK, ILLINOIS

AUTOMATIC REGULATOR

Application filed January 12, 1928. Serial No. 246,143.

This invention relates to automatic controlling apparatus in general, but more particularly to apparatus of this kind for governing or controlling a boiler furnace damper, thereby to automatically govern or control the rise and fall of the steam pressure.

Generally stated, the object of the invention is to provide a novel and improved construction and arrangement whereby a rotary motor, of any suitable character, such, for example, as an electric motor, may be employed for supplying the motive power for operating the damper or other means to be controlled, as well as for operating the compensating device that modifies or controls the motor controller, which latter is controlled by the said pressure responsive device connected with the steam pressure from the boiler, or with any other source of fluid pressure.

It is also an object to provide certain details and features of construction and combinations tending to increase the general efficiency and the desirability of an automatic controlling apparatus of this particular character.

To the foregoing and other useful ends, the invention consists in the matters hereinafter set forth and claimed, and shown in the accompanying drawings, in which, —

Fig. 1 is a side elevation, more or less diagrammatic in character, of an automatic controlling apparatus embodying the principles of the invention.

Fig. 2 is a similar view, showing a different form of the invention, with certain parts thereof in vertical section to facilitate the illustration of the mode of operation of the invention.

As thus illustrated, and referring more particularly to Fig. 1, it will be seen that the invention comprises a steam pressure responsive diaphragm device 1, connected by a pipe 2 with the boiler pressure, or with any other suitable source of fluid pressure which it is desired to maintain at some predetermined degree of pressure, as nearly as possible. The counterbalance lever 3 is fulcrumed at 4, as shown, and the diaphragm has a knife edge 5 which supports the said

lever in the substantially horizontal position shown. The counterbalance weight 6 is supported on a traveler 7 having wheels 8 that travel on the upper edge of the lever 3, in the manner shown. A rotary motor 9, such as an ordinary electric motor, is provided in stationary position over the diaphragm pressure responsive device, and is provided with one drum 10 having a cable 11 wound thereon, and with another drum 12 having a cable 13 wound thereon. The cable 11 is connected with the lever 13 of the damper 14 in the smoke flue of the boiler furnace, the other end of this lever having a counterbalance weight 15 for opening the damper. The cable 13 is connected to the traveler 7 at 16, as shown. An operating weight 17 for operating the traveler 7 to the right on the lever 3, is connected by a cable 18 with the traveler 7 at 19, this cable 18 being trained over a sheave 20 carried on the distal end of the lever 3, as shown. Thus the motor, when it rotates in the direction indicated by the arrow 21, causes an opening movement of the damper 14, and at the same time moves the traveler 7 to the left, and raises the weight 17, in a manner that will be readily understood. On the other hand, when the motor is operated in the opposite direction, the damper 14 has a closing movement, and the traveler 7 moves toward the right because of the pull thereon by the weight 17, in a manner that will be readily understood. Said motor, if an electric motor is used, is preferably of the positive start and stop type, being self-braking, so that it will stop instantly as soon as the electric current supply is interrupted. The motor controller, for governing the supply of electric current to the motor, comprises a pair of stationary contacts 22 and 23, together with a movable contact 24 carried by the outer end of the arm or lever 3, or by any suitable portion of this lever, for it is the up and down motion of this lever 3 which is most conveniently utilized as the means for controlling the electric switch or motor controller which is necessary for the starting and stopping of the said motor. It will be understood that the contacts 22 and 23 are included in cir-

cuits which also include the motor 9 and a suitable source of electric current supply. Thus the electric circuit controller serves also to limit the up and down movement of the counterbalance arm. A second compensating device, for more or less modifying the action of the traveler 7 or main compensating device, thereby to govern the electric controller, comprises a cam plate 25 rigidly mounted, as shown, or in any suitable or desired manner, on the traveler 7, adapted when its upper surface strikes the stationary stop roller 26 to force the lever 3 downward, and adapted when its under surface strikes the similar stop roller 27 to force the lever 3 upward, thus in effect modifying the action of the traveler 7 and its function of causing a modifying effect on the tilting movements of the lever 3, which tilting movements are caused by the diaphragm device 1 previously mentioned.

In operation, when the pressure in the device 1 falls below a certain point, the arm 3 starts downward from its normal position, 25 as shown, and when the contact 24 engages the contact 23 a circuit is closed through the source of current (not shown) and the motor 9, causing the latter to rotate in the direction indicated by the arrow 21, thus 30 causing the damper 14 to have an opening movement. This operation of the motor also causes the traveler 7 to move to the left until the lower surface of the cam plate 25 engages the stop roller 27, and when this 35 happens the consequent slight upward movement of the cam plate will necessarily cause the arm 3 to start rising, and will thereby separate the contacts 24 and 23, thus positively stopping the rotation of the motor 40 and the opening movement of the damper before waiting for the counterbalance 6 to effect this action by reason of the mere fact of its movement closer to the fulcrum 4, which in itself would be sufficient to finally 45 cause the upward movement of the lever 3, but the cam action between the plate 25 and the roller 27 accelerates or slightly advances this action and the consequent stopping of the motor in the manner explained. There- 50 after, when the pressure in the device 1 rises to a predetermined point, the lever 3 will be raised, causing the contact 24 to engage the contact 22, thus closing a circuit through the source of current and the motor 9, caus- 55 ing the motor to rotate in an opposite direction, thereby causing the damper 14 to have a closing movement, and, at the same time, the operation of the motor causes the weight 17 to pull the traveler 7 to the right, and this 60 would continue until the weight 6 pulls the lever 3 down to normal position, but the engagement of the upper surface of the cam plate 25 with the roller 26 hastens or accelerates this action more or less, causing the 65 lever 3 to be positively moved downward to

break the circuit and thereby positively stop the motor in time to prevent the action of the weight 6 from pulling the arm 3 down far enough to cause the contact 24 to engage the contact 23, which latter action would immediately start a reverse movement of the lever 3, which would be undesirable. Therefore the shifting of the weight 6 in one direction, when the pressure in the device 1 falls, shortens the period of rest of the contact 24 against the contact 23, and the shifting of the weight 6 in the opposite direction, when the pressure in the device rises, shortens the period of rest of the contact 24 against the contact 22, and this period of rest in each case is still further shortened by the action of the cam plate 25 and the stops 26 and 27 in the manner explained. What is meant, of course, is that the period of rest is shortened as compared with what would take place if the position of the weight 6 was fixed on the arm 3, so that it would not be automatically moved back and forth thereon.

In Fig. 2 the construction is similar to that previously described, except that in this case a third compensating device is provided, comprising a frame 28 suspended from the drum 29 of the motor 30 by a cable 31, this frame having a cylinder 32 rigid with its lower portion. The upper and lower ends of the cylinder are connected by a by-pass 33 having a regulating valve 34 therein. The plunger or piston head 35 in the cylinder has a rod 36, to the upper end of which the cable 37 is attached, this cable being supported by a sheave 38 on the motor base, and having its other end connected at 39 to the traveler shown, this traveler being similar to the one previously described. A weight 40 is slide- 100 able up and down on the rod 36 and is sup- 105 ported by a cable 41, which is in turn sup- 110 ported on a stationary sheave 42, the other 115 end of this cable being connected at 43 with the upper end of the rod 36 previously mentioned. A suitable liquid is carried in the 120 cylinder 32, above and below the piston head 125 or plunger. Thus, when the motor 30 is ro- 130 tating to open the damper 44, the frame 28 is being lowered, such lowering being re- 135 tarded by the dashpot arrangement, and the 140 consequent downward movement of the 145 dashpot plunger or piston head on its rod 36 will cause the cable 37 to pull the traveler 150 to the left, against the pull of the weight 45, thus shifting the counterbalance weight 155 46 from one position to another on the coun- 160 terbalance arm 47, in the manner previously 165 explained. Then, when the motor is re- 170 versed to cause the closing movement of the 175 damper, the dashpot contrivance is pulled 180 upward by the motor, thus allowing the 185 weight 45 to pull the traveler to the right. 190 Thus the dashpot and its weight form a part 195 of the operating connection between the mo- 200 tor and the traveler.

5 Figs. 1 and 2, it will be understood, are partly diagrammatic, showing how the three contacts of the electric controller can be connected to binding posts on the motor, it being understood that the internal circuits of the motor can be of any suitable or well-known character, reversible rotary motors of this kind being very common and well understood.

10 Thus in either form of the invention there are instrumentalities characterized by horizontal movement compensation acting vertically for automatically operating a motor controller, as in each case the weight (6 or 15 46) is movable horizontally to provide a variable compensation, such weight acting vertically to operate the controller.

Obviously, with the electric circuit controller comprising the contacts 22, 23, and 24, the arm 47 is not required to shift any 20 mechanical parts, or to do any mechanical work, but is only required to move up and down in order to close one or the other of the contacts 22 and 23 of the electric controller. This means, of course, that the arm 25 47 may have only very slight movement, just sufficient to open and close the contacts, thereby to start and stop the motor. As the motor is a rotary motor, it has no self-imposed or self-contained stopping means, as 30 does a reciprocating motor, and is characterized by continuous rotary motion until stopped by the cessation of the electric current supply. Moreover, with the dashpot 35 arrangement shown in Fig. 2 of the drawings, means are provided for moving the weight 46 on the arm 47, while this arm is in normal position, and while the motor is not running. For example, the pressure may 40 have fallen to a low point, and the electric controller starts the motor 30, and the latter opens the draft damper, or operates the other means to be controlled, and at the same time moves the weight 46 on the arm 45 47, away from the weight 45, whereby before a rise in the pressure the electric controller or switch will be automatically opened, by the shift of the weight, in the manner fully explained. However, at such time the desired high pressure may not have been 50 reached, and under such circumstances the dashpot arrangement shown in Fig. 2 constitutes a means for moving the weight 46 on the arm 47, toward the weight 45, after the arm has returned to normal position, thereby to again operate the switch or electric controller and start the motor again, if the pressure has not been raised sufficiently, thus keeping the draft damper open until 55 the steam pressure has been built up to the desired degree. Thus the desired high pressure mark is reached sooner and more definitely than in cases where the compensating weight on the counterbalance arm can only move when the motor is running, and when

the counterbalance arm is either up or down. Consequently, the weight 46 may be and is at times moving while damper 44 is stationary. Thus the electric controller is of importance, and of advantage, as it relieves 70 the counterbalance arm of any mechanical function, such as the operation of valves or other mechanical parts, and confines the function of the up and down movement of this arm merely to the opening and closing 75 of electrical contacts.

Without disclaiming anything, and without prejudice to any novelty disclosed, what I claim as my invention is:

1. In automatic controlling apparatus, the combination of a motor for operating the means to be controlled, a counterbalance arm, pressure responsive means for causing said arm to move up and down, a traveler on said arm, a counterbalance weight on said traveler, means whereby said motor is operative to cause said traveler to move back and forth on said arm, elements cooperating with said arm to control said motor, and a compensating device serving to modify the action of 90 said traveler and weight.

2. A structure as specified in claim 1, said compensating device comprising stops adjacent the opposite limits of motion of said traveler, and a cam plate on said traveler disposed at an angle to move under one stop to press the counterbalance arm downward and adapted to move over the other stop to cause said arm to move upward.

3. A structure as specified in claim 1, said compensating device comprising a dashpot and weight contrivance suspended from the motor and traveler, forming an operating connection between the motor and traveler.

4. In automatic controlling apparatus, in combination with means to be controlled, a rotary motor for operating said means, a controller for starting and stopping said motor, and for reversing the rotation of said motor, and instrumentalities for automatically operating said controller, thereby to automatically control said means, said instrumentalities comprising a counterbalance arm and a weight on said arm, and a pressure responsive device for causing said arm to move up and down, said weight being movable horizontally from one position to another on said arm, and said motor having means for automatically shifting said weight from one position to another, forming a main compensating device to modify the action of said instrumentalities, together with a second compensating device operative to move said weight while said arm is in normal position and while said motor is not in operation and serving to 115 modify the action of said main compensating device.

5. In automatic controlling apparatus, in combination with means to be controlled, a rotary motor for operating said means, a con-

troller for starting and stopping said motor, and for reversing the rotation of said motor, and instrumentalities for automatically operating said controller, thereby to automatically control said means, said instrumentalities comprising a counterbalance arm and a weight on said arm, and a pressure responsive device for causing said arm to move up and down, said weight being movable horizontally from one position to another on said arm, and said motor having means for automatically shifting said weight from one position to another, forming a main compensating device to modify the action of said instrumentalities, together with a second compensating device serving to modify the action of said main compensating device, and a third compensating device serving to modify the action of said other compensating devices.

20. In automatic controlling apparatus, in combination with means to be controlled, a rotary motor for operating said means, a pressure operated controller for stopping and starting said motor, a compensating device operated by said motor, and instrumentalities operative to actuate said compensating device while said motor is not in operation, after said motor has stopped, thereby to again start said motion.

25. 7. A structure as specified in claim 6, said compensating device comprising a counterbalance arm with a weight movable along said arm.

30. 8. A structure as specified in claim 6, said compensating device comprising a counterbalance arm with a weight movable along said arm, and said instrumentalities having a connection by which to move said weight while said arm is in normal position.

35. Specification signed this 7th day of January, 1928.
